UNITED STATES PATENT OFFICE

JAMES STEWART CRAIB, OF MONTREAL, QUEBEC, CANADA, ASSIGNEE, BY MESNE ASSIGNMENTS, TO ALEMITE CORPORATION, OF CHICAGO, ILLINOIS, A CORPORATION OF DELAWARE

LUBRICATOR

Application filed November 30, 1928, Serial No. 151,712, and in Great Britain December 12, 1925.

My invention aims to provide improvements in lubricators of the type wherein the outlet is automatically regulated to produce a substantially uniform delivery of lubricant.

In the drawings, which illustrate preferred embodiments of my invention:—

Figure 1 is a sectional elevation of a cup showing the stem carried by the cup body, and showing the position of the parts when the cup is full of lubricant;

Fig. 2 is a section similar to Fig. 1, but showing the relation of the parts of the cup when the cup is empty;

Fig. 3 is an elevation of the body portion of the cup shown in Figs. 1 and 2;

Fig. 4 is a section on the line 4—4 of Fig. 1, showing, in dotted lines, the position of the means for holding the piston-actuating spring compressed during the filling operation of the cup;

Fig. 5 is an elevation of the piston and piston-carrying portion of the cup; and

Figs. 6 and 7 show two sectional elevations of a lubricant cup adapted to be charged with lubricant from a lubricant gun or the like, and showing the parts in the positions they occupy when the cup is empty and when full.

Referring first to the cup illustrated by Figs. 1 through 5, I have shown a body part 1, a piston-carrying part 2 and a part 3 for coupling together the piston-carrying part 2 and body part 1. The coupling of the parts is effected by bayonet slots 4 formed in the lower edge of the body part 1 (Fig. 3) and pins 5 shown in Fig. 5, the parts being coupled, as shown in Figs. 1 and 4.

The piston-carrying part 2 has a hollow extension 6 provided with keys 7 on opposite sides and this keyed extension passes through an opening 8 of similar cross-section in the part 3 as shown in Figs. 1, 2 and 4. The piston portion 9 fits the inner wall of the body part 1 and a spring 9a is interposed between this piston portion 9 and the part 3 to exert a pressure upon the lubricant in the body part 1 (or reservoir). The upper end of the extension 6 has a restricted orifice 10 and the lower end is screw-threaded to secure the cup to a part to be lubricated.

A lubricant flow controlling element or stem 11 (which in this instance is shown as tapered) is suspended from the top of the body part 1 and is provided with a threaded extension 12 which is threaded through the top of the body part 1 (Figs. 1 and 2) so that the flow controlling element or stem 11 may be adjusted longitudinally with relation to the orifice 10. A nut 13 is provided to lock the stem in its adjusted position.

Any method may be used in filling the cup constructed as shown in Figs. 1 through 5, but I have shown a cup which may be filled by hand when it is taken apart. The operation of filling is simple, it being merely necessary to lift the body of the cup, and then turn it. During the lifting part of the operation, the keys 7 are disengaged from the slots, in the part 3, and when it is turned, the spring is held in compressed position as shown in Fig. 5. The body 1 may then be turned to release it from the pins 5, and may be pulled away from the piston-carrying part 2. When the reservoir has been filled, the cup may be put together again and is then ready to discharge lubricant as shown in Fig. 1.

As the body part 1 travels downwardly relative to the piston 9, the degree of compression of the spring 9a decreases, so that the pressure, tending to force the lubricant to the bearing, also decreases.

By reason of the stem 11 being carried downwardly with the body portion 1 of the cup, it passes through the outlet orifice 10 and the passage through which the lubricant is forced is controlled by the movement of the stem. This counteracts the effect due to the decrease in the compression of the spring, so as to provide for a substantially uniform flow of lubricant to the bearing.

When using lubricants of various viscosities, or, when for any reason it is desirable to change, or regulate, the flow of lubricant, this can be easily and quickly effected by first slackening the lock nut 13, and then turning the screw-threaded extension of the stem 11 to raise or lower the stem, with respect to the piston. Thus, when a tapered stem 11 is used, as shown in the drawings, the size

of the annular orifice can be made greater or smaller as desired throughout the complete travel of the part 1 relative to the part 2, and therefore a greater or smaller uniform flow of lubricant may be obtained.

5 The cup shown in Figs. 6 and 7 employs substantially the same principles for the control of the flow of lubricant through the discharge orifice and the regulation of the stem as described in connection with Figs. 1 through 5, except that the cup is provided with means whereby the reservoir may be filled by a gun or the like without taking the cup apart. Also the stem 11 is carried by 10 the piston 9, which reciprocates in the body portion 1.

In this instance, the adjustment of the stem 11 is made relative to the piston 9 by means of a rotatable sleeve 14 which passes 20 through the top of the body part 1 and a non-cylindrical extension 15 of the stem, beyond the threaded portion. This non-cylindrical portion 15 passes through a hole 16 of similar cross-section formed in the sleeve 14, 25 so that, when the outer end 17 of the sleeve is rotated, the stem will be adjusted upwardly or downwardly relative to the piston 9. The non-cylindrical extension also serves as an indicator, whereby it indicates the relative 30 position of the piston 9 in the cup, and therefore gives a general idea of how much lubricant remains in the reservoir.

This cup may be filled through an opening 18 adjacent the bottom of the cup, and a 35 usual ball check valve 19 is provided, so that lubricant may be forced into the cup but cannot return. A cover 20 for the opening 18 is also provided to keep dust and dirt therefrom.

40 In both types of cups illustrated, the external adjustments are conveniently located, so that the stem may be adjusted at any time and without taking the cup apart.

45 My invention is not restricted to the illustrative embodiment of the invention shown and described.

Claims:

1. A lubricator cup comprising a body portion providing a lubricant reservoir, a 50 flow controlling element carried by said body portion, a piston in said reservoir adapted to be secured to a part to be lubricated, spring means providing for relative movement between said piston and said body portion to force the lubricant from said reservoir and a 55 discharge orifice through said piston in which said flow controlling element moves to control the flow of lubricant through said orifice as the body portion moves relative to 60 the piston.

2. A lubricator cup comprising a body portion providing a lubricant reservoir, a flow controlling element carried by said body portion, a piston in said reservoir, spring 65 means providing for relative movement be-

tween said piston and said body portion to force lubricant from said reservoir, a discharge orifice through said piston through which said flow controlling element moves to control the flow of lubricant through said orifice as the flow controlling element moves relative to the piston and means extending externally from said body portion whereby said stem may be adjusted to control the discharge of lubricant.

3. A lubricant cup comprising a body portion providing a lubricant reservoir, a tapered stem carried by said body portion, a piston in said reservoir and a spring for moving the stem relative to said piston, said piston having a lubricant discharge orifice therethrough, through which said stem moves to provide a reducing resistance to the expulsion of lubricant as said spring weakens.

4. A lubricant cup comprising a body portion providing a lubricant reservoir, a tapered stem carried by said body portion, a piston in said reservoir and a spring for pressing the stem toward said piston, said piston having a lubricant discharge orifice therethrough through which said stem moves to provide a reducing resistance to the expulsion of lubricant as said spring weakens, and means extending externally from said body portion whereby said stem may be adjusted relative to the body portion for controlling the discharge of lubricant from the cup.

5. A lubricant cup comprising a body part 100 providing a reservoir, a piston part located in said reservoir, means providing a discharge orifice, an adjustable stem located within said cup and adapted to pass into the discharge orifice to regulate the delivery of lubricant through said discharge orifice with 105 relation to the pressure placed upon the lubricant in the reservoir, said stem having an adjustably threaded connection with one of said parts and an extended handle connection projecting exteriorly of said cup whereby the 110 position of said stem will be directed and may be varied axially relative to the discharge orifice by operating the extended handle connection to adjust the threaded connection of the stem.

6. A lubricator cup comprising a body portion providing a reservoir, a piston in said reservoir, means providing a discharge orifice, a spring for moving said piston to discharge lubricant from the cup through said orifice, an adjustable stem forming part of the cup assembly and adapted to pass into said orifice to regulate the discharge of lubricant therethrough and indicating means extending from said stem to the outside of said cup, 120 thereby to indicate the quantity of lubricant in said cup, said indicating device when rotated being adapted to adjust said stem axially to vary the relation with the said discharge orifice.

7. A lubricator cup comprising a body portion providing a lubricant reservoir, a stem carried by said body portion, a piston in said reservoir, spring means providing for relative movement between said piston and said body portion to force the lubricant from said reservoir, and a discharge orifice through said piston through which said stem may move to control the flow of lubricant through 10 said orifice as the stem moves relative to the piston, said stem having an extension passing upwardly through the top of said body portion and provided with means whereby said stem may be adjusted longitudinally 15 relative to the body of the cup, said means providing for holding said stem in adjusted position.

8. A lubricant cup comprising a body part providing a lubricant chamber, a piston fixed 20 with relation to the part to be lubricated, means providing a lubricant discharge orifice, a stem for controlling the flow of lubricant through said orifice, means for moving the body part relative to the piston to 25 place the lubricant under pressure and means for adjusting said stem to control the flow of lubricant of various viscosities.

9. A lubricator cup comprising a body portion providing a lubricant reservoir, a stem carried by said body portion, a piston in said 30 reservoir, spring means providing for relative movement between the piston and body portion, means providing a discharge orifice and adjustable means for holding the spring 35 means in compressed position so that the cup may be easily assembled and disassembled.

10. A lubricator cup comprising a body portion providing a lubricant reservoir, a piston located in said reservoir, an apertured 40 plate forming part of the body portion, spring means provided between the apertured plate and the piston for imparting relative movement between the piston and body portion, an extension carried by the piston and 45 extending through the aperture in the said plate, means providing a discharge orifice for the lubricant reservoir and rotatably adjustable key and slot means provided by the plate and extension, said key and slot means 50 being operable to hold the spring means in compressed position so that the cup may be easily assembled and disassembled.

In testimony whereof, I have signed my name to this specification.

JAMES STEWART CRAIB.

CERTIFICATE OF CORRECTION.

Patent No. 1,791,300.

Granted February 3, 1931, to

JAMES STEWART CRAIB.

It is hereby certified that error appears in the printed specification of the above numbered patent requiring correction as follows: Page 2, line 111, for "directed" read indicated; and that the said Letters Patent should be read with this correction therein that the same may conform to the record of the case in the Patent Office.

Signed and sealed this 17th day of March, A. D. 1931.

M. J. Moore,
Acting Commissioner of Patents.
